BENJAMIN E. D. STAFFORD AND FREDERICK K. LANDGRAF, OF PITTSBURGH, PENNSYLVANIA, ASSIGNEES TO FLANNERY BOLT COMPANY, OF PITTSBURGH, PENNSYLVANIA.

STAY-BOLT CONNECTION FOR BOILERS.

1,210,013.

Specification of Letters Patent. Patented Dec. 26, 1916.

Application filed November 6, 1915. Serial No. 60,051.

To all whom it may concern:

Be it known that we, BENJAMIN E. D. STAFFORD and FREDERICK K. LANDGRAF, citizens of the United States, and residents of Pittsburgh, in the county of Allegheny and State of Pennsylvania, have invented certain new and useful Improvements in Stay-Bolt Connections for Boilers; and we do hereby declare the following to be a full, clear, and exact description of the invention, such as will enable others skilled in the art to which it appertains to make and use the same.

Our invention relates to improvements in stay bolt connections for boilers.

In an application for patent filed by Benjamin E. D. Stafford, October 30th, 1915, No. 58,868, a sleeve is secured by welding to the outer face of the outer sheet of the boiler and carries and supports the stay bolt, the head of which is mounted for universal movement on a curved seat formed on the inner face of the sleeve.

This invention consists in a roof plate having openings for the passage of the bolt and provided with a depressed concave seat around each opening to form a seat for the bolt head, a sleeve or cover plate welded to the roof plate around the bolt opening, and a screw cap closing the outer end of the sleeve or the opening in the cover plate.

In the accompanying drawings, Figure 1 is a view partly in section and partly in elevation of our improvement, and Fig. 2 is a view of a modification.

1 represents a roof plate or sheet of a locomotive boiler provided with an opening 2 for each stay bolt, the said opening being slightly larger than the shank 3 of the bolt so as to permit of the relatively free lateral movement of the bolt in the opening. The plate 1 is bent inwardly at each bolt opening, as at 4, and the depressed or bent portion is provided on its outer face with a curved seat 5 for the head 6 of the bolt. The head of the bolt therefore rests directly against the outer face of the outer plate of the boiler and as the seat for the head is depressed, the head if spherical, projects but slightly beyond the outer plane of the outer plate 1.

Welded to the plate 1 around the depressed seats therein, and consequently around the bolt openings, are the sleeves 7, one for each bolt. The inner end of each

sleeve is milled to conform to the surface of the plate against which it bears, so that it will have an extended and solid bearing on said plate, and the welding of the sleeve to the plate is done by the oxyacetylene, electric, or any other approved form or method of welding.

The sleeve 7 is provided at its outer end with internal threads for the attachment of the cap 8 which latter forms a closure for the head of the bolt.

The welding composition or filler, for fusing the sleeve to the plate, is preferably applied at the outer and inner lower edges of the sleeve as shown at 9 and 10, so that the union between the plate and sleeve is of a homogeneous character whereby all the advantages of a sleeve integral with the plate are obtained.

If desired, a bolt with a head flattened on top may be used, as shown in Fig. 2. With such a construction the head will be wholly within the depressed seat in the plate, hence instead of using a sleeve, a flat cover plate 11 may be welded to the plate 1, the bolt 20 hole in the cover plate being closed by the screw cap 8a.

With this improvement the bolt bears directly on the outer plate which latter receives all shocks and stresses incidental in the installation of the bolt, and also all stresses due to boiler pressure, while the housing for the bolt takes only the collapsing stresses.

It is evident that changes in the construction and relative arrangement of the several parts might be made without avoiding our invention and hence we would have it understood that we do not restrict ourselves to the particular construction and arrangement of parts shown and described, except as required by the scope of the appended claims.

Having fully described our invention what we claim as new and desire to secure by Letters-Patent, is:

1. In stay bolt connection for a boiler, the combination of a boiler plate having a depressed seat for the head of the stay bolt and a bolt opening at the bottom of the depression, a housing welded to the plate around the depression, and a screw cap for closing said housing.

2. In stay bolt connection for a boiler, the combination of a boiler plate having a depressed seat for the head of the stay bolt,

100

105

110

- and a bolt opening at the bottom of the depression, a sleeve welded to said plate around the depressed seat, and a screw cap closing the outer end of the sleeve.
- 5 3. In stay bolt connection for a boiler, the combination of a boiler plate having a depressed seat for the head of the stay bolt, and a bolt opening at the bottom of the depression, a housing welded to said plate around the depression and open for the passage of the bolt, a bolt the head of which
- 10

is seated in said depression, and a screw cap closing the opening in the housing.

In testimony whereof, we have signed this specification in the presence of two subscribing witnesses.

BENJAMIN E. D. STAFFORD.
FREDERICK K. LANDGRAF.
